United States Patent Office

Des. 207,088
Patented Mar. 7, 1967

207,088

BASEBALL GLOVE

Richard E. Bates, Ashland, Ky., and Theodore E. Javor, Roselle, Ill., assignors to Wilson Athletic Goods Mfg. Co., Inc., River Grove, Ill., a corporation of Delaware

Filed June 3, 1966, Ser. No. 2,549

Term of patent 14 years

(Cl. D2—361)

FIG. 1 is a front perspective view of a baseball glove showing our new design; and

FIG. 2 is a rear perspective view thereof.

The essential features of our design reside in the full line disclosure on the drawing.

We claim:

The ornamental design for a baseball glove, substantially as shown and described.
